ABSTRACT OF THE DISCLOSURE

The blades of a variable pitch propeller are rotated to vary their pitch by a double-acting, fluid-operated drive unit composed of a unitary double piston structure which is driven axially in either direction by fluid pressure in two opposed cylinders which coact with respective ones of two piston portions of the piston structure. The piston structure is coupled to the propeller blades to impart rotary motion to them upon axial movement. The guiding and sealing surfaces of the two piston elements are preferably cylindrical, are coaxial with each other and are of equal diameters.

BACKGROUND OF THE INVENTION

This invention relates to variable pitch propellers such as those employed in ships, turbines, pumps and the like.

Variable pitch propellers of various types have been proposed and used in the past in ships, turbines, pumps and other types of bladed devices. In the usual variable pitch propeller, the propeller blades are rotatably mounted on a hub and are coupled to a blade pitch control mechanism which selectively pivots the blades about their mounting axes to vary their pitch and set them at a desired pitch. A number of forms of pitch control mechanisms employing mechanical, electro-mechanical and hydraulic principles have been suggested.

Many known hub designs, especially in the case of large diameter propellers, present difficult design problems on account of the weight and axial length of the hub. In ship propellers, for example, it is often of considerable importance to keep the length of the hub as small as possible, having regard for the clearance in the propeller aperture, and to keep the weight of the hub as low as possible, having regard for the bearing loads and the bending stresses in the propeller shaft. An excessive length and weight of the hub also has an unfavorable effect upon the operating characteristics of certain kinds of turbines.

Some previously proposed pitch control mechanisms have one or more hydraulic pistons which are coupled by axial piston rods to power transmitting devices which transmit the piston movement to the propeller blades. These piston rods impart pivotal movement to the blades by means of sliding blocks or links. Some types require hubs which are extremely heavy in relation to the total propeller weight and are excessively long in relation to the axial space which is required for the fitting and pivoting of the blades in the hub. To be reliable in service, they require precision manufacture and large, strong parts, partly for guiding and sealing the pistons in the cylinders and partly for the guiding of devices which transmit power to the blades.

SUMMARY OF THE INVENTION

The purpose of this invention is to provide a propeller hub structure embodied in a pitch control mechanism which is free of many of the disadvantages found in

2

existing propellers, and particularly to provide a hub structure which is light in weight, compact in size, strong and durable, essentially trouble-free, and of low cost as to construction, maintenance and repair.

More particularly, a propeller, according to the invention, includes a fluid-operated pitch control mechanism, preferably a hydraulic-operated mechanism, located in the hub. The mechanism comprises a double piston structure in the form of a rigid unitary member composed of two piston elements which are axially movable in two separate opposed fluid cylinder units, one of which is positioned on each side of the double piston structure in the axial direction of movement of the same, the two cylinders being fixed in the propeller hub. The cylinder units and the piston elements form two fluid-pressure chambers for actuating the double piston structure, and power transmitting elements couple the double piston structure to the propeller blades such that axial motion of the piston structure imparts rotary motion to the blades to vary their pitch.

Each of their piston members, i.e., the members constituting moving walls or parts of the fluid chambers, making up the double piston structure may have either an internal or an exterior cylindrical surface arranged to slide along a mating cylindrical surface of the companion cylinder unit. The cylinder units, i.e., those parts that constitute fixed walls of the fluid chambers, similarly, of course, may have either internal or external cylindrical surfaces along which the companion piston member slides. Preferably, the cylindrical guiding and sealing surfaces of the pistons and cylinders are coaxial and of equal diameters.

DESCRIPTION OF THE DRAWINGS

For a better understanding of the invention, reference may be made to the following description of exemplary embodiments, taken in conjunction with the accompanying drawings, in which:

FIG. 1 is a side view in section, taken generally along an axial plane, of one embodiment of the invention;

FIG. 2 is an end view in section through the embodiment of FIG. 1, the section being taken generally along the plane represented by the lines A—A and in the direction of the arrows;

FIG. 3 is a side view in section taken along a generally axial plane of another embodiment of the invention, the view being in generally schematic form;

FIG. 4 is a generally schematic view in section taken along an axial plane of a third embodiment according to the invention;

FIG. 5 is a generally schematic, side sectional view taken along an axial plane of a fourth embodiment; and

FIG. 6 is a generally schematic, side view in axial section of another embodiment of the invention.

DESCRIPTION OF EXEMPLARY EMBODIMENTS

The embodiment illustrated in FIGS. 1 and 2 includes a hub body 1 which is constructed to carry four propeller blades 3. Within the body is an axially disposed cavity or bore which receives, inter alia, a hydraulic pitch-control mechanism (described below). The hub body 1 has four peripherally spaced recesses 7 for pivotal mounting of the propeller blades 3. (Only the blade flanges 9 and the innermost root portions of the blades 3 are shown on the drawings.) Each propeller blade 3 is rotatably attached for pitch variation to the hub body 1 by means of a mounting structure composed of bearing ring 11 which is fastened, such as by threads, to the hub body 1 and a crank pin ring 13 which is attached to the blade flange 9 and provided with a crank pin 15 (FIG. 2). The crank pin ring 13 is pivoted on a journal bearing 17 positioned in the hub body recess 7.

The hub body 1 is fastened to a flange 19 on a propeller shaft drive 21, and the propeller shaft 21 has a central, axial bore 23. Extending through the bore 23 is a pipe 25 which is arranged for movement in the axial direction through the shaft bore. The pipe 25 and the annulus in the bore 23 between the pipe 25 and the walls of the bore both serve as supply and return conduits for a hydraulic fluid to the hydraulic mechanism in the hub 1. At the opposite end of the hub body from the propeller shaft flange 19 are an end cover 27 and a hub cone 29, 10 the cone and cover being sealed to the body.

The hydraulic mechanism provides for the transmission of power from the pressure fluid to each propeller blade 3 through the crank pins 15 on the crank pin rings 13 and includes a one-piece double piston structure 31 located in the cavity or bore 5 of the hub body. The double piston structure 31 consists of two piston portions including on one side a portion 33 which in the form shown in FIGS. 1 and 2 has an external cylindrical guiding and sealing surface 35 which seals against an internal cylindrical face 37 on the end cover 27, these elements being sealed by a seal ring 39 and thereby defining a closed fluid chamber 41 for the pressure fluid. On the other end of the piston structure 31 is a piston portion 43 which seals against an external guiding and sealing surface 47 of a cylinder unit 49, which is affixed to the hub body 1, thereby defining a chamber 51 for pressure fluid actuating the piston portion 43.

The cylinder unit 49 has an opening 53 in its end wall which is sealed by a seal 55 to and receives a tube section 57. The tube section 57 is joined at one end to the piston structure 31 and is provided with an axial bore 59 having a wider section 61 at the shaft end and a narrower section 63 at the piston end. The pipe 25 extends through the wider section 61 of the bore 59 and is coupled at the end of this section to the narrower section 63, thus connecting it to the fluid chamber 41 for supply and return of pressure fluid to and from the chamber 41. The annular space in the bore 23 between the pipe 25 and the wall of the bore communicates with the wider section 61 of the bore 59 and thence through radial holes 65 to the fluid chamber 51 for supply and return of pressure fluid to the chamber 51. The supply and return of pressure fluid to and from the chambers 41 and 51 are controlled by a suitable valve control unit which will generally be remote from the propeller hub and located at a control point. Any appropriate source of fluid pressure, and preferably hydraulic pressure, can be employed.

In one form of known control system for variable pitch propellers, the flow of hydraulic fluid to and from the hydraulic mechanism in the hub is regulated by means of a pilot valve located in the hub. Such a pilot valve is operated by axial movement of a pipe corresponding to pipe 25 in FIG. 1. Other than for this purpose the pipe 25 usually serves only as a supply pipe for pressure fluid while the annulus between the pipe and the shaft bore wall serves as a return conduit. An arrangement of a pilot valve in the hub is shown in Swedish Patent No. 93,872 and can with advantage be used in a propeller according to the present invention.

Referring particularly to FIG. 2, the double piston structure 31 is provided with lugs 67, one for each propeller blade 3, which extend out generally radially from the piston structure 31 through openings 69 in the hub body 1. These openings 69 allow the lugs 67 to move in an axial direction within the hub body 1 a distance necessary for any desired rotational movement of the propeller blades 3. The lugs 67 are preferably located on the central part of the double piston 31. In the form shown, each lug 67 is coupled to a propeller crank pin 15 by means of a sliding block 71 in which the crank pin 15 is rotatably pivoted. The sliding blocks 71 are arranged to slide in bearing grooves 73 machined in the lugs 67 with guide surfaces perpendicular to the longitudinal axis of the piston structure 31.

It is desirable in the propeller pitch control mechanism according to the invention to construct the unit such that one of the piston portions, e.g., 33, has an external guiding and sealing surface 35 sliding within a fixed inner seal 39 on its cylinder unit 37 while the other piston unit 43 has an inner seal 45 sliding along an external guiding and sealing surface 47 of its cylinder unit 49. With this construction, the possibility of the piston structure sticking as a result of asymmetrical load from the propeller blades 3 is considerably reduced. A particularly short hub length is possible if, as shown in FIGS. 4 and 5, one of the cylinder units is recessed in the propeller shaft 21. It is also desirable that the guiding and sealing surfaces between the two piston portions and the respective cylinder units be coaxial and of equal diameters. This construction provides operation of the device without any pumping effect in the cavity 5 as the piston structure is moved back and forth.

Because the double piston structure 31 is guided along two stationary cylinder units (37 and 49), only two cylindrical guiding and sealing surfaces (35 and 47) need to be accurately machined over their entire axial length while the opposite cylindrical surfaces only need to be machined in the areas adjacent to their seals (39 and 45). Fabrication of the unit is thus simplified, and the costs are correspondingly reduced.

FIGS. 3 to 6 show, in generally schematic form, various alternative constructions embodying different arrangements in the guiding and sealing of the piston portions 33 and 43 of the double piston structure 31 along the two cylinder units in the hub body 1. The reference numerals for each figure are the same as those applied to the embodiment of FIGS. 1 and 2, but with the addition of a letter suffix for each alternative embodiment. Inasmuch as the structure and operation of the embodiments of FIGS. 3 to 6 are basically the same as those of the embodiment of FIGS. 1 and 2, elaborate description of FIGS. 3 to 6 is unnecessary, and reference can be made back to the foregoing description, taken in conjunction with the points mentioned below.

The embodiment of FIG. 3 shows an arrangement corresponding substantially to that in FIG. 1. The piston portion 33a of the double piston structure 31a remote from the propeller shaft 21 is provided with an external guiding and sealing surface 35a arranged to slide along an internal seal 39a on the fixed cylinder unit 37a. The piston portion unit 43a adjacent to the propeller shaft 21 is tubular and provided with an internal seal 45a arranged to slide along the external guiding and sealing surface 47a of the cylinder unit 49a.

FIG. 4 shows an arrangement in which the piston portion 33b is tubular and provided with an internal seal 77b which is arranged to slide along the external guiding and sealing surface 79b of the cylinder unit 81b. The piston portion 43b is provided with an external guiding and sealing surface 83b arranged to traverse an internal seal 85b on the cylinder unit 87b.

In the embodiment of FIG. 5, the piston unit 33c is provided with an external guiding and sealing surface 35c which is arranged to traverse the internal seal 39c of the cylinder unit 37c. The piston portion 43b is similarly provided with an external guiding and sealing surface 83c arranged to traverse the internal seal 85c on the cylinder unit 87c.

According to FIG. 6 the piston portion 33d is tubular and has an internal seal 77d which is arranged to slide along an external guiding and sealing surface 79d of the cylinder unit 81d. The piston portion 43d is also tubular and provided with an internal seal 45d arranged to slide along the external guiding and sealing surface 47d of the cylinder unit 49d.

The above-described embodiments of the invention are intended to be merely exemplary, and those skilled in the art will be able to make numerous variations and modi-

ifications of them without departing from the spirit and scope of the invention.

We claim:

1. In a variable pitch propeller for use in ships, pumps, turbines and the like which includes a hub carrying a plurality of propeller blades, each blade being mounted for rotation about an axis generally radially of the hub for adjustment of its pitch, the combination therewith of a mechanism for rotating the blades to adjust their pitch comprising a unitary double piston structure carried in the hub and including a common wall portion transverse to the hub axis and first and second skirt portions mounted on the common wall portion and disposed axially on the hub, the first skirt portion having an external cylindrical surface and the second skirt portion having an internal cylindrical surface; means defining a first cavity in the hub including a member fixed on the hub and having an internal cylindrical surface slidably mating with the cylindrical external surface of the first piston skirt portion thereby to define a first fluid chamber on one side of the piston common wall portion; means defining a second cavity in the hub including a member fixed on the hub and having an external cylindrical surface slidably mating with the cylindrical internal surface of the second piston skirt portion thereby to define a second fluid chamber on the other side of piston common wall portion; the said cavities being located in opposed relation and said second skirt portion having a portion of its outer wall formation located in proximity to the intersections with such skirt portion of the said pivot axes of the propeller blades; a crank linkage between the piston and each of the propeller blades located in proximity to the said intersections and including elements associated with the said proximate portion of the second skirt portion of the piston structure for coaction with an element on each blade; and means for selectively communicating one or the other of the fluid chambers with a source of fluid pressure, the piston being shifted in one direction axially of the hub in response to application of fluid pressure in one of the chambers and being shifted in the opposite direction axially of the hub in response to application of fluid pressure in the other of the chambers, thereby to change the pitch of the blades.

2. The combination according to claim 1 wherein the crank linkage includes a lug on the said proximate portion of the piston second skirt portion inwardly of each blade and having a crank pin slot formed therein, a crank pin on each blade extending into the respective crank pin slot, and bearing means interposed between each crank pin and crank pin slot.
  - 5 3. The combination according to claim 1 wherein the piston first sleeve portion extends in one direction from the wall portion, and the second sleeve portion extends in the other direction from the wall portion.
  - 10 4. The combination according to claim 3 wherein the first sleeve portion extends rearwardly from the wall portion relative to the shaft carrying the propeller and the second sleeve portion extends forwardly from the wall portion.
  - 15 5. The combination according to claim 1 further comprising a propeller drive shaft coupled to the hub and including a bore therethrough, a conduit extending through the bore in the shaft and movable axially of the shaft and coupled to the piston structure for movement therewith, the outer surface of the conduit being spaced from the wall of the bore to define a passage, means associated with the piston structure communicating the interior of the pipe with one of the fluid chambers and communicating the passage with the other fluid chamber.
  - 20 6. The combination according to claim 1 wherein the cylindrical surfaces of the respective piston portions and cavities are coaxial and of substantially equal diameters.
  - 25
